UNITED STATES PATENT OFFICE.

LEONARD FORBES BECKWITH AND ARTHUR BECKWITH, OF NEW YORK, N. Y.

IMPROVEMENT IN COKE-OVENS.

Specification forming part of Letters Patent No. 105,413, dated July 19, 1870.

To all whom it may concern:

Be it known that we, LEONARD FORBES BECKWITH and ARTHUR BECKWITH, both of the city, county, and State of New York, have invented a new and useful Improvement in Coke-Ovens, of which the following is a full, clear, and exact description, reference being had to the accompanying drawing, forming part of this specification, and in which—

Figure 1 represents a vertical longitudinal section of a coke-oven, taken through its side wall, mainly as indicated by the line *xx* in Fig. 3, which is a transverse section through the line *yy* in Fig. 1. Fig. 2 is a central longitudinal section through the coking-chamber of the oven.

Similar letters of reference indicate corresponding parts.

Our invention consists in a novel arrangement of vertical and horizontal flues, chambers, and communications, whereby the gases evolved in cooking are utilized in a most advantageous manner.

The invention also includes a tongue construction of fire-bricks applied to form the flues through which the gases are circulated, and serving to brace the walls of the oven.

The invention is applicable to coking various kinds of coal, either separately or mixed, with or without a cementing substance—such, for instance, as coal-tar or asphalt.

Referring to the accompanying drawing, A is the chamber which is charged with the coal to be coked. The gases are first drawn from above the coal through one or more drop-flues, B, which conduct them down through the side wall of the oven until they reach the level of the top of the coal in the oven, or thereabout. At this level the gases are collected in a flue, C, which conducts them first horizontally, and afterward in a downward direction, and through a communication, *b*, to one end of a chamber, D, situated under the floor of the oven, and extending nearly the whole length and breadth of the latter. From this chamber D, at the opposite end of it to that at which they are admitted, said gases pass or are drawn off, through a communication, *c*, into a horizontal return-flue, E, in the side wall of the oven, below the flue C, and

which return-flue conveys the gases backward and forward the length of the oven to an escape-flue or chimney, F.

The ends of the flues C and E, where they reach the outer walls of the oven, are provided with small openings *d*, which should have stoppers for graduating the admission of air and completing the combustion, and which serve as apertures for cleaning the flues.

The following advantages, among others, are obtained for this arrangement of vertical and horizontal flues, chambers, and communications. The gases are conducted in a direct manner from the top of the oven to the chamber D, under the floor of the oven, where the greatest heat is required, thereby avoiding useless or destructive expenditure of heat on the side walls. The chamber D, also, by its large capacity relatively to the flues, insures a slow movement of the gases under the floor of the oven, thereby giving ample time for the transmission of heat to the coking-chamber and diminishing friction, which eases the draft, nor do the flues in the side walls present sufficient changes from a direct line or course to interfere with such ease of the draft. Furthermore, the amount of flue-space in the side walls above the top level of the coal in the oven, where the heat from the gases has no effect upon the coke, and only operates to injure the flues, is reduced to a minimum.

The floor of the coking-chamber A we prefer to build of slabs of fire-proof material, and of the form shown in the drawing, as such facilitate the transmission of heat to the coking-chamber and present few joints, and by arranging them as shown they are kept in form and sustained by the weight of the side walls. The flues in the side walls are formed of fire-bricks G, having tongues *ee* on their edges, and applied to only partially enter—that is, to the depth of their tongues—the side walls of the oven, or walls separating adjacent ovens, thereby bracing said walls, and preventing the coal, in its expansion within the oven, from altering the shape of the side walls; also admitting of a thinner side wall being used, which favors the transmission of heat into the oven, and reduces cost and labor of construction. These tongued fire-bricks are arched or

grooved, as shown, whereby they are made to form troughs for the dust of the flues to collect in, and to facilitate the cleaning of the flues, also whereby the capacity of the flues is increased.

What we claim as our invention, and desire to secure by Letters Patent, is—

1. The arrangement of the vertical and horizontal flues, the chambers, and communications, substantially as and for the purpose herein set forth.

2. The tongued fire-bricks, constructed and applied substantially as herein described, to form the flues and brace the walls of the ovens.

LEONARD F. BECKWITH.
ARTHUR BECKWITH.
